FIGURE 3

FIGURE 4

FIGURE 5

FIG. 1 is a side elevational view of a rotor assembly for a detent tuning mechanism for a television tuner showing my new design;

FIG. 2 is a sectional elevation taken along the line 2—2 of FIG. 1;

FIG. 3 is an elevation as seen from the right of FIG. 1;

FIG. 4 is an elevation as seen from the left of FIG. 1; and

FIG. 5 is an enlarged fragmentary section taken along the line 5—5 shown on FIG. 1.

I claim:

The ornamental design of a rotor assembly for a detent tuning mechanism for a television tuner, as shown and described.
